(57) **CLAIM**

The ornamental design for a rice sheet machine, as shown and described.

DESCRIPTION

FIG. 1 is a perspective view of a rice sheet machine showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and

FIG. 7 is a bottom plan view thereof; and,

FIG. 8 is a partially enlarged front elevational view thereof at the area 8 of FIG. 2.

The broken lines illustrate portions of the rice sheet machine and form no part of the claimed design. The single dot-dash broken lines define the boundaries of the claimed design and form no part of the claimed design.
